UNITED STATES PATENT OFFICE.

HEINRICH MAX COLDITZ, OF MILWAUKEE, WISCONSIN.

HEEL FOR BOOTS AND SHOES.

No. 841,935.

Specification of Letters Patent.

Patented Jan. 22, 1907.

Application filed May 17, 1905. Serial No. 260,911.

To all whom it may concern:

Be it known that I, HEINRICH MAX COLDITZ, a citizen of the United States, residing at Milwaukee, State of Wisconsin, have invented certain new and useful Improvements in Heels for Boots and Shoes, of which the following is a full, clear, and exact specification.

This invention relates to certain new and useful improvements in heels for boots and shoes; and it has for its objects, among others, to provide an improved detachable heel which can be easily applied to or removed from a boot or shoe and which when in position can be securely fastened so as to prevent undue movement or accidental displacement, yet allowing of the ready removal of the heel when it becomes worn, and even should the heel become so worn before discovery as to wear the plate which is outermost a new plate can be provided at small cost.

The invention embodies a flanged plate designed to be secured to the shoe or boot and a co-operating plate attached to the upper side of the detachable heel and flanged to interengage with the flanges of the plate on the shoe or boot, the construction and interengagement being such that when the heel is slid into place on the shoe or boot it is drawn tightly against the latter, so as to make a close joint and prevent dirt or other foreign substances from getting in between the heel and the shoe or boot bottom. The plate on the heel is provided with flanges or extensions which are bendable and which are adapted to be bent down against a portion of the shoe at the forward portion of the heel and securely hold the heel against displacement, as it must slide backward before it can be removed, and these extensions when bent into position securely prevent such movement.

Other objects and advantages of the invention will hereinafter appear and the novel features thereof will be specifically defined by the appended claim.

The invention is clearly illustrated in the accompanying drawings, which, with the numerals of reference marked thereon, form a part of this specification, and in which—

Figure 1 represents in reversed plan the sole of the shoe or boot, with its plate, and the detachable heel, with its plate, separated. Fig. 2 is a perspective view, with a portion broken away, showing the heel secured in position. Fig. 3 is a cross-section on the line 3

3 of Fig. 2. Fig. 4 is a sectional view of the plate which is attached to the sole, Fig. 5 is a similar view of the plate which is attached to the heel. 60

Like numerals of reference indicate like parts throughout the several views in which they appear.

Referring now to the details of the drawings, 1 designates a portion of the sole of a boot or shoe, to the under side of the heel portion of which is secured in any suitable manner, as by the nails or the like 2, a plate 3, the body portion of which lies flat upon the under side of the heel portion, while at its side edges are the turned-up flanges 4, the plate at the rear end being cut away upon opposite sides of the center, as seen at 5, and the extreme rear end between such cut-away portions being provided with the upturned 75 flange 6, all as clearly illustrated. By "upturned" I mean that the flanges are in a plane above that of the body portion, so as to leave a space for a purpose which will soon be made apparent. 80

7 designates the plate which is designed to be attached to the detachable heel 8. This heel may be of rubber or any other suitable material, as may be desired, and upon its upper side it is recessed, as seen at 9, and 85 within said recess the said plate 7 is disposed, the object of the recess being to allow the plate to set within the heel sufficiently that it will not interfere with the close contact of the heel with the heel portion of the 90 sole when the heel is in position thereon. The plate 7 may be formed of one integral piece, or it may be of two pieces, as shown, the portion 10 being seated in a subrecess 11 in the recess 9 and having a flange 12 resting 95 on the upper wall of the recess 9 and a second portion 13 resting upon the flange 12, leaving a space 14 between the said portion 13 and the upper face of the body portion of the part 10. The space 14 is closed at its rear end, while the portion 10 at its front end is provided with a lug or extension or extensions 15 for a purpose soon to be described. 100

In practice with the plate 3 secured to the under side of the sole the plate 7, in one or two pieces, may be secured to the heel in any suitable manner, as by rivets 16, which are passed through the part 13 and the flange 12 of the part 10 and the heads of the rivets disposed in countersunk openings 17 in the 110 outer face of the heel, which holes may or may not be filled with rubber, cement, or

other suitable material. The rivets 16 may also be used to unite the part 13 and flange 12, and the projecting ends may be riveted into plates sunk into the material of the heel. 5 Rivets may also be dispensed with altogether, and the part 13 may be sufficiently broadened so as to project beyond the edge of the heel, whereupon the edge can be clenched into the heel, thus firmly securing the metal plates to 10 the heel. The mode of securing is immaterial and may be varied at liberty without departing from the nature and scope of my invention.

When the heel is placed in position with 15 the flanges 4 of the plate 1 engaging in the spaces 14, the heel is pushed back into position, when the flange 6 will enter the space at the rear of the heel beneath the portion 13, and the heel will be drawn tightly up against 20 the under face of the sole, against which it firmly bears. Then the lugs or extensions 15 are turned up against the shoulder or wall 18 of the front portion of the heel portion of the sole, as shown, and thus the heel will be kept 25 from accidental displacement; but it can be easily removed, when desired, by bending the said lugs or extensions straight, and then the heel is free to slide rearward.

By reason of the cut-away portions 5 between 30 the flanges 4 and 6 I am enabled to provide said flange 6 so as to insure the engagement of the flanges 4 beneath the edges of the plate 13 and also insure the engagement of the flange 6 within the space 14, 35 which latter is closed at its rear end, and the flanges 4 being offset from the plane of the plate 3 the two plates are drawn into close contact as they are slid one upon the other.

Importance is attached to the fact that the flanges are cut away upon opposite sides of the center, as shown. By this means I provide an easy catch when the heel is to be slid into place on the shoe. As the flanges are very tight for, the reason that the heel is to be drawn tightly into place, there is naturally a very small space between the same. Therefore the flanges must necessarily be made so as to catch easily the flange on the shoe. By cutting away the flanges the smaller portions remaining are easily deflected or bent as the parts are slid together, and thus the heel is more easily forced into position than it would be if a greater amount of metal existed.

What is claimed as new is—

The combination with a shoe and a plate 55 secured thereto with its body portion lying flat upon the under side of the heel portion of the shoe with its side edges provided with turned-up flanges with the rear end of the plate cut away at opposite sides and the extreme rear end between such cut-away portions having a turned-up flange, of a detachable heel, a plate secured thereto within a recess in the upper face of the heel and provided with a recess and a subrecess with 65 flanges with an intervening space closed at its rear end and its front end provided with integral bendable lugs bent up against and directly engaged with the front of the heel portion of the sole, substantially as and for the purpose specified.

In testimony whereof I affix my signature.

HEINRICH MAX COLDITZ.

In presence of—

ADOLPH G. SCHWEFEL,
CLARA L. SYDON.
